[57] CLAIM

The ornamental design for a golf club grip, as shown and described.

DESCRIPTION

FIG. 1 is a top plan view of a golf club grip showing my new design;

FIG. 2 is a front elevational view thereof;

FIG. 3 is a left-side elevational view thereof with a portion of a golf club shaft shown in dashed lines for environmental purposes, the opposite side appearing essentially the same;

FIG. 4 is a rear elevational view thereof; and

FIG. 5 is a bottom plan view thereof.

FIG._1.

FIG._3.

FIG._2.

FIG._4.

FIG._5.
